(57) **CLAIM**

The ornamental design for a cradle for digital camera, as shown and described.

DESCRIPTION

FIG. 1 is a perspective view of the top, front and left side of a cradle for digital camera showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross sectional view thereof at 8—8 shown in FIG. 6;

FIG. 9 is a cross sectional view thereof at 9—9 shown in FIG. 6;

FIG. 10 is a cross sectional view thereof at 10—10 shown in FIG. 6; and,

FIG. 11 is a reference view showing the usage thereof. The elements shown in broken lines are for illustrative purposes only and form no part of the claimed design.
